UNITED STATES PATENT OFFICE.

HERBERT D. BEMAN, OF WESTFIELD, MASSACHUSETTS, ASSIGNOR TO
CYPRIAN J. KING, OF SAME PLACE.

WHIP.

SPECIFICATION forming part of Letters Patent No. 629,886, dated August 1, 1899.

Application filed April 14, 1899. Serial No. 712,964. (No model.)

To all whom it may concern:

Be it known that I, HERBERT D. BEMAN, a citizen of the United States, residing at Westfield, in the county of Hampden and State of Massachusetts, have invented new and useful Improvements in Whips, of which the following is a specification.

My invention relates to whips generally, and especially to the class employing a ratan or rawhide stock or center and provided with an exterior braided or other covering.

My invention consists in the parts and the construction and combination of parts forming the improved whip, which I will hereinafter describe and claim.

In the accompanying drawings, forming part of this specification and in which similar letters of reference indicate corresponding parts, Figure 1 is a side elevation of a portion of a whip with the outer covering removed to disclose the spirally-wound load at the butt-end. Fig. 2 is a similar view with the outer covering in place and the handle portion otherwise finished. Fig. 3 is an enlarged part-elevation and part-sectional view of the handle portion. Fig. 4 represents a rawhide center, the spirally-disposed load and an outer covering forming a stock, the latter being broken away to expose the center and load.

In this art the practice has been for years and still is to load the butt-end of whips whenever it is possible. This practice has been followed with all classes of whips except those of the cheapest character. The loading of certain classes of whips has been attended with more or less difficulty and considerable loss, due to the breakage of the stock either during the course of the manufacture of the whip or after the whip has been put to limited use. In the case of what is termed a ratan "through-whip"—*i. e.*, a whip including a stock formed of a piece of ratan tapering from butt to tip and built up with paper around the butt to obtain the desired size and shape—many efforts have been made to load the handle, and among which efforts may be noted the boring in at the butt and inserting a metal plug. This proved unsatisfactory and more or less objectionable because so much of the thickness of the stock was removed to form the bore for the plug that the stock was so weakened that

even with the greatest of care exercised during the process of manufacture many of the whips had to be discarded because of the breaking of the stock, this occurring in many instances even before the whip was completed. Another recognized class of whips includes those in which a rawhide center is used as a substitute for the more costly whalebone, the rawhide extending in some cases one-half way through the whip, while in other cases it extends to a greater distance—say two-thirds the length, more or less. These latter whips are usually loaded by means of a cast-iron plug or spike driven into the butt, while in another class of whips a rawhide center is used extending clear through the whip from butt to tip, with the end of the rawhide showing at the butt, the rawhide being contained within a stock composed of ratan or wood; but such a whip could not be loaded by the methods in vogue, as in the one case the cast-iron plug or spike could not practically be bored through, as in doing so so much of the stock would be removed as to render the use of the spike practically valueless, as the spike was then found to be too fragile.

The difficulties attending the manufacture of such whips as are above alluded to have not heretofore been cured as far as I know, although the trade is constantly demanding a successfully-loaded, cheap, strong, and pliable whip of the character before noted. Extensive experiment has shown me that the desired objects are attainable by using as a load for the handle portion of a whip a piece of metal which is spirally coiled around the exterior of the stock and just beneath the outer braided or other covering or around the rawhide center in the whip employing such a center and stocking it up by the methods usually employed in the manufacture of whips.

In carrying forward my invention I construct the stock A in the usual manner and of ratan or any other material which may be used to form the stock. To give the stock the desired size and shape at the butt-end, it is usual to build it up with paper, as shown at a in Fig. 1. The stock so produced I load by spirally coiling about its butt-end a strip of metal B, preferably lead, the edges of whose

individual coils are open, as shown at *b*, Fig. 1, the terminals of the said strip being secured to the stock by pins *c* or other well-known means, although, if desired, the pins 5 may be omitted, as the lead strip may be coiled sufficiently tight as to insure its being held frictionally in place during the process of braiding or putting on the exterior covering *C*. The disposition of the metal strip exterior to the stock gives to the whip the so much sought for load at the butt-end, and the load is fixed in position without any of the dangers and losses due to cutting away or boring of the stock which heretofore have 15 been common in the manufacture of whips having an inserted plug.

Aside from the successful loaded feature of my whip there are other advantages which flow from the employment of the spiral strip 20 and which are appreciated by the users of whips. For instance, the open edges of the spirally-coiled strip enable the stock to substantially retain its original flexibility, and when the outer covering *C* is braided or otherwise put on it sinks into the groove formed 25 by the open edges, so that the completed whip will have a flexible and loaded handle spirally grooved to increase its ornamentation and provide a ventilated grip which will 30 have a pleasant feeling to the hand.

In Fig. 4 I illustrate my invention applied to the through rawhide whip before alluded to. In this instance the desirable results are obtained by coiling the strip *B'* about the

rawhide or other center *C'*, as shown, and 35 then stocking the handle portion up in the usual manner, as shown at *D'*, it being understood that in said Fig. 4 a portion only of the outer flexible covering *E'* of the whip is shown and that in the finished whips the 40 usual ferrules *D* and *E* and other well-known accessories will be employed to heighten the attractiveness of the article.

Having thus described my invention, what I claim as new, and desire to secure by Letters 45 Patent, is—

1. In a whip having a stock, or center adapted to extend from butt to tip, a strip of metal wound spirally about and confined wholly to the handle portion thereof and exterior thereto, and having open edges to preserve the flexibility of the stock, or center, and a covering exterior to the metal strip. 50

2. In a whip the combination of a stock, a load therefor consisting of an exterior spirally-wound strip of metal, and a flexible outer covering, said strip having open edges to preserve the flexibility of the stock and form a spiral groove into which the outer covering is drawn to produce a spirally- 55 grooved handle. 60

In testimony whereof I have hereunto set my hand in presence of two subscribing witnesses.

HERBERT D. BEMAN.
